US0D1009862S

(12) **United States Design Patent** (10) **Patent No.:** **US D1,009,862 S**
(45) **Date of Patent:** **** Jan. 2, 2024**

(54) **DATA STORAGE DEVICE**

(71) Applicant: **SecuX Technology Inc.**, Hsinchu (TW)

(72) Inventors: **Kuan-Tsan Huang**, Hsinchu (TW);
Alice Bo-Wen Chang, Hsinchu (TW);
Bill Chen, Hsinchu (TW)

(73) Assignee: **SecuX Technology Inc.**, Hsinchu (TW)

(**) Term: **15 Years**

(21) Appl. No.: **29/846,070**

(22) Filed: **Jul. 13, 2022**

(30) **Foreign Application Priority Data**

Jan. 28, 2022 (TW) 111300580

CLAIM

The ornamental design for a data storage device, as shown and described.

DESCRIPTION

FIG. 1 is a front and bottom perspective view of a data storage device showing our new design;

FIG. 2 is a rear and top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The even spaced broken lines shown in the drawings depict portions of the article that form no part of the claimed design.

1 Claim, 8 Drawing Sheets
